APPARATUS FOR MIXING MATERIALS

Frederick L. Craddock, Rochester, N. Y.

Application October 24, 1938, Serial No. 236,721

6 Claims. (Cl. 259—109)

This invention relates to apparatus for mixing materials, and it deals particularly with the mixing or intimate blending of two or more liquids with each other, and also the mixing of one or more liquids with one or more finely divided or pulverulent solids. It finds use in a wide variety of arts. For instance, in the mixing of food products, liquid and solid chemicals, beverages, the making of emulsions, the mixing of oils and 10 pigments in the manufacture of paints and lacquers and also the tinting and coloring thereof, the mixing of pastes, plasters, syrups, creams, ointments, greases and soaps etc., mixing apparatus play an important part in the final quality 15 of the product.

Although various forms of mixing apparatus have been heretofore proposed and several different types are in actual use, they are not altogether successful. One reason why the present 20 forms of apparatus fail to achieve the results desired is that little or no consideration has been given to the fundamental principles involved in the mixing of materials, and the further fact that prior workers in this art have taken existing barrels, vats, or tanks of more or less standard design and have adapted them, without change of shape, to the mixing of liquids by merely suspending a propeller therein or by passing a shaft through the tank wall and equipping it with 25 a propeller.

The problem involved in the mixing of liquids, the dissolving of solids in liquids, the making of emulsions and suspensions, and in the agitating of such blends and suspensions to keep them 30 uniform and of a standard quality is one of obtaining an intimate and uniform blend with a minimum expenditure of time and energy and avoiding any tendency of the ingredients to separate or stratify and without the violent beating and local action sought for in churning and other operations, where the object is separation rather than combination of the various ingredients.

The most common type of mixing apparatus 35 in general use probably is a vertical cylindrical tank provided with a rotary mixing element extending vertically downward into the tank, the axes of the rotary mixer and the tank being coincident. Such an arrangement serves merely to rotate bodily the entire mass of liquid and is 40 therefore very inefficient as a blending or mixing apparatus. The use of horizontal rotating paddle wheels, the axes of which extend inwardly through the side walls of the tank, is also old, but these also do little more than impart rota- 45

tion to the body of the liquid without breaking up stratification and effecting an intimate intermixture or blend.

For fairly light liquids, particularly where the depth of the body is nearly equal to the breadth, 5 an improvement upon the foregoing methods has been found in the adaptation of a principle which has been in use for many years—that of placing a propeller upon a shaft passing horizontally through the side of the tank, the propeller being 10 near the tank wall and thrusting straight across. The current thus formed is forced upward upon striking the opposite wall; then back across the top and down to the propeller again, travelling 15 in a substantially vertical plane and leaving the 10 sides of the tank untouched and stagnant. This method has been tried out in finished sweetened condensed milk in tanks ten feet in diameter, and it effected a blend in from two to three hours. 20 It is obvious, however, that a propeller capable 25 of thus turning over so large a body of finished milk and of overcoming the choking or retarding effect of the right angled baffle presented by the opposite tank wall must be of large size and rotate so rapidly as to develop a detrimental 25 thrashing effect.

In connection with this method, another method is worthy of mention in which the propeller is mounted upon a short shaft extending exactly vertically through the center of the bottom of 30 the tank. The directly upward thrust of this propeller produces a fountain effect which is intended to spread outward in all directions at the top and return via the sides of the tank to the 35 propeller. In light fluids, where the depth of the body about equals the breadth, this method is reported as quite successful, but in so heavy, viscous a product as cold, sweetened condensed milk, and particularly in comparatively shallow 40 bodies where the upward current could hardly distribute itself over the correspondingly large area, this method seems only a little better, by reason of the greater possible speed of the propeller, than the old vertical, over head driven 45 method previously mentioned.

It is accordingly the primary object of this invention to devise a mixing apparatus embodying a tank or drum for the materials to be mixed which is of special design, and a mixing and circulating device is so located in the tank as to 50 cooperate with the material in novel manner to thoroughly and intimately intermix all of the material in the tank, and yet without setting up any harmful heating or thrashing actions that 55

would tend to separate, rather than combine the ingredients of the materials to be mixed.

A further important object is to provide a mixing apparatus embodying a horizontal drum-like tank, in which the materials are mixed, and a propeller mechanism located in the tank and operable to mix the material and so disposed as to set up a whirling wheel-like circulation of the material, so as to successively present all portions thereof to the mixing action of the propeller.

Another object is to provide a horizontal drum-shaped mixing tank and a mixing mechanism located adjacent the bottom of the tank for intimately mixing the material and also driving the material across the bottom and upwardly for preventing ingredients thereof from settling out, and setting up a wheel-like, over-and-over circulation of the material.

A further object is to provide a horizontal drum-like mixing tank with a mixing device adjacent the bottom of the tank for setting up a wheel-like over-and-over circulation of the material, and deflector means for deflecting the material into the mixing device as it undergoes circulation, to insure that the material will be repeatedly acted upon thereby.

Another object is to provide a drum-like mixing tank with a propeller mounted on a shaft entering the tank below the level of the material therein, and to so construct the propeller, that in addition to propelling the material, it will also exert a clawing, tearing, or cutting action thereon to insure complete disintegration of the various components.

Further objects of the invention will become apparent as the specification proceeds in connection with the annexed drawings, and from the appended claims.

In the drawings:

Figure 1 is a front elevational view, with certain parts broken away and in section in order to more clearly illustrate the parts involved, of a mixing apparatus embodying my invention;

Figure 2 is a top plan view of the apparatus shown in Figure 1;

Figure 3 is a side elevational view of the apparatus shown in Figure 1, and it illustrates the parts as they appear when the device is viewed from the right-hand side of that figure; and

Figure 4 is an end view of the propeller shown in Figures 1 to 3 inclusive.

With continued reference to the drawings, wherein like reference characters have been employed to indicate like parts throughout the several views thereof, in the present illustrated embodiment of the invention, the apparatus is mounted upon a base A, comprising a pair of longitudinal angle members 10 and 11, and a pair of transverse channel members 12 and 13. The parts are preferably welded together and are supported above the floor by a plurality of legs 14, which are also welded thereto.

In the present instance the apparatus is illustrated as being mounted on legs so as to elevate it above the floor and adapted for portable use in the plant. For instance, by picking the unit up with a special truck it may be moved about in the plant and its flexibility and range of usefulness greatly increased. However, it is to be understood that the invention is not limited to use with any particular form of base, as it may be permanently mounted on location.

Supported upon longitudinal members 10 and 11, and preferably secured thereto by means of a pair of welded plates 15 and 16, and a pair of

angle members 17 and 18 is a steel drum B having a cylindrical wall 21, and a pair of preferably flat end walls 22 and 23. Materials to be mixed are introduced into, and finished materials removed from the drum by way of an opening 24, which is closed by removable closure 25, having a handle 26, and it seats upon a flange 27 welded to the top of the drum at the margin of the opening.

Although the illustrated form of drum is preferred, the invention is not limited thereto as it may be made of wood, ceramic material or any other suitable material, and it may, if desired, be non-circular externally. It is, however, preferably generally cylindrical internally and I have also found that the best results are secured when the width of the tank; namely, the distance between drum heads 22 and 23, is less than the diameter of the drum. The drum is preferably constructed of steel for general utility, but its composition will vary in accordance with the materials which are to be handled by the drum. For instance, if corrosive liquids are to be mixed the tank may be constructed of corrosive resistant metal or it may be provided with a corrosion resistant lining.

I have discovered that by providing a tank of the character disclosed and equipping it with a propeller or mixing mechanism so disposed as to set up a circular over-and-over circulation of the materials to be mixed, a superior mixing action is obtained, both when finely divided solids are to be incorporated with liquids, and also when two or more liquids are to be blended, one with the other, because the material is repeatedly returned to and subjected to the mixing action of the propeller.

Various forms of propelling mechanism may be used, but I preferably employ the one illustrated and which will now be described.

Referring to Figures 1, 2 and 4, a propeller 31 is carried by a shaft 32 which extends through a bearing and sealing assembly S and is driven by means of a gear reduction R and a motor M. Secured to transverse member 12 by means of a plurality of cap screws 33 is a bracket 34. Motor M and gear reduction unit R are mounted upon bracket 34 in any suitable manner and the gear reducer terminates in the driving shaft 36.

Although, if desired, the propeller may extend through the cylindrical portion 21 of the drum, in the particular embodiment of the invention illustrated, the drum is preferably modified to provide a recess into which certain of the parts are nested for the sake of compactness and other advantages to be hereinafter pointed out.

As seen in Figures 1, 2 and 3, the cylindrical portion of the drum is cut away and flat plates 37, 38, 39 and 40 are welded in place to provide a pocket into which a portion of the speed reducer and the sealing assembly S are located. Mounted on plate 40 are a pair of deflector or guide or "spillway" members 42 and at their upper ends they merge with, or are connected to the lower ends of a pair of guide or deflector members 43 which are secured to cylindrical 21 of the drum. The guide or deflector members are operable to guide or deflect the rotating mass of material into the path of the propeller, as will be pointed out more in detail hereinafter.

A shaft 32 projects from the seal and bearing assembly S into the mixing chamber, and carries a propeller 31 having a hub portion 82.

The detailed bearing and seal assembly S is not claimed in this case, but is reserved for incorporation in a divisional application.

Although the propeller may assume various forms, and two or more propellers may be mounted on the shaft, I preferably employ one propeller of special form, and it is more clearly illustrated in Figure 4. It comprises three blades 86 which terminate in a plurality of claws or fingers 87 which I have discovered effect a remarkably rapid disintegration of any lumpy aggregations that may be present in the material to be mixed and they also exert what may be termed a "tearing", cutting or clawing, action, which greatly assists in mixing and emulsifying the mixture. Blades 86 may also be provided at their leading edges with a plurality of cutting fingers 88, which also function to break down the material into a mixable state, and as the propeller blades are located rearwardly thereof they pick up the material subsequent to disintegration and propel it. Blades 86 therefore function to mix the material and simultaneously definitely propel it in the tank while fingers 87 and 88 effect a further mixing of the material because, aside from disintegrating any aggregations that may be present in the material, they effect an intermixture of the material, regardless of whether a pulverant solid is being mixed with a liquid, or two or more liquids are being blended, one with the other.

No claim is made to the propeller, per se, as is more fully shown and claimed in my copending application Serial No. 236,720, filed October 24, 1938, for "Mixing apparatus".

The present embodiment of the invention has been illustrated as employing a propeller driven through a gear reduction, but if desired it may be directly driven by the motor, or shaft 32 may project away from the drum and carry a pulley to be driven by any desired prime mover. Also, the propeller shaft has been illustrated as being disposed normal to a vertical plane containing the axis of the drum but it is to be understood that if desired, it may assume other angles, depending upon the requirements of the particular installation at hand. Similarly the propeller may be disposed to the left rather than to the right (Figure 1) of a vertical plane containing the axis of the drum, depending upon the particular mixing action desired.

I have illustrated what may be termed a "single unit" form of the invention, as the width of the drum is less than the diameter and a single propeller assembly is associated therewith for mixing and circulating the material, but it is to be understood that if desired the drum width may be increased to any desired multiple thereof to increase the capacity thereof, and one or more partitions employed to divide it up into compartments of the proper size, without departing from the spirit of the invention. If desired, the partitions may be perforated to allow circulation between the various compartments.

As the material undergoes a wheel-like circulation in the tank any tendency of it to stratify into two or more layers is positively prevented, due to the fact that the material is moving up on one side of the drum and down on the other side. Also, there are no stagnant or "dead" spots, in which the material may become pocketed and not be subjected to the mixing action of the propeller. The wheel-like circulation of the material is not sufficiently high to effect centrifugal separation of the ingredients, but it is to be particularly observed that should solids cling to the cylindrical wall or travel in close proximity to it, the deflector members will deflect it down over

the inclined wall, and it will be discharged over the lower edge of the latter directly into the propeller, where it will be intimately mixed with the liquid. Therefore, any unusually heavy or difficultly mixable solids are constantly maintained in suspension and cannot settle in the bottom of the drum. 5

The invention may be embodied in other specific forms without departing from the spirit or essential characteristics thereof. The present 10 embodiment is therefore to be considered in all respects as illustrative and not restrictive, the scope of the invention being indicated by the appended claims rather than by the foregoing description, and all changes which come within 15 the meaning and range of equivalency of the claims are therefore intended to be embraced therein.

What is claimed and desired to be secured by United States Letters Patent is: 20

1. In an apparatus for mixing liquids and other materials, a generally cylindrical mixing tank disposed with its axis substantially horizontal and having a smooth cylindrical wall for the major portion of its circumference, propeller means located in the bottom of said chamber and operable to intermix said material and effect a substantially circular bodily movement thereof about the axis of said chamber as a center, and deflector means associated with said cylindrical wall of 30 said chamber, and located rearwardly of said propeller means with respect to the direction of rotation of said material, for causing the latter to be deflected and enter said propeller along a predetermined path. 35

2. The apparatus defined in claim 1, wherein said propeller means comprises a shaft projecting into said chamber and having at least one propeller thereon, said shaft being substantially normal to a vertical plane passing through the 40 axis of said chamber and said propeller being located in proximity to said deflector means.

3. In a mixing apparatus, a horizontal mixing drum having a generally cylindrical side wall, said drum being disposed with its axis substantially horizontal, a pair of deflector members provided on the interior of said cylindrical wall, said deflector members converging downwardly, so as to deflect material rotating in the drum to be deflected toward the center of said cylindrical wall, said wall being provided with a substantially flat wall adjacent the lower ends of said deflector members which inclines inwardly and downwardly toward the bottom of said drum, and a pair of further deflector members mounted on said flat wall and disposed with their upper ends in proximity to the lower ends of said first-named deflector members. 50 55

4. The mixing apparatus defined in claim 3, together with a shaft extending into said drum below said flat wall and having a propeller mounted thereon adjacent the lower edge of the latter, for exerting a mixing and circulating action upon material gravitating downwardly between said deflector members and over the lower 60 edge of said flat wall. 65

5. The mixing apparatus defined in claim 3, together with a second substantially flat wall disposed substantially vertically in said drum and joined at its upper edge to said first-named flat 70 wall and joined at its lower edge to the cylindrical wall of said drum, and a propeller shaft extending through said second flat wall and carrying a propeller thereon adjacent the lower edge of said first-named flat wall. 75

6. In a mixing apparatus, a hollow drum-like chamber having a generally cylindrical inwardly facing side wall, and a pair of end walls, said drum being disposed with its axis substantially horizontal, so that said cylindrical wall has a high side and a low side, said side wall having a diameter at least as great as the spacing between said end walls, whereby said chamber assumes the form of a hollow disc, and propeller means coacting in contacting engagement with the material to be mixed for causing the latter to intimately intermix and simultaneously setting up intermingling currents therein which travel in a

generally circular path about the axis of said chamber as a center, said propeller means comprising a shaft having at least one propeller mounted thereon and located in said chamber below and substantially transversely of the axis thereof and adjacent the low side of said wall and to one side of a vertical plane containing the axis of said chamber, said propeller being disposed wholly within the plane of said inwardly facing wall of said chamber and submerged in 10 the body of material in the latter. 5

FREDERICK L. CRADDOCK.
